(57) **CLAIM**

The ornamental design for the soup mug, as shown and described.

DESCRIPTION

FIG. 1 is a perspective view of the soup mug that emphasizes the top of the soup mug.

FIG. 2 is a perspective view of the soup mug that emphasizes the bottom of the soup mug.

FIG. 3 is a front view of the soup mug.

FIG. 4 is a rear view of the soup mug.

FIG. 5 is a right side view of the soup mug.

FIG. 6 is a left side view of the soup mug.

FIG. 7 is a top view of the soup mug; and,

FIG. 8 is a bottom view of the soup mug.

The broken lines form no part of the claimed design.
